UNITED STATES PATENT OFFICE.

DONALD S. BARROWS, OF ROCHESTER, NEW YORK, ASSIGNOR, BY MESNE ASSIGNMENTS, TO THE SYMINGTON COMPANY, A CORPORATION OF MARYLAND.

JOURNAL-BOX-FASTENING MEANS.

Application filed October 30, 1924. Serial No. 746,799.

The invention relates to side frames for car trucks and more particularly to means for interlockingly connecting journal boxes and side frames.

To this end, the principal object of the invention, generally considered, is to provide a side frame having a journal box engaging portion, together with means cooperating with the side frame and with a member within the journal box for interlockingly connecting the side frame and journal box.

Another object of the invention is to provide means for interlockingly connecting a journal box to a side frame, said means preventing the removal of the journal box under service conditions by co-acting with a member within the journal box so as to eliminate extraneous fastening devices such as lugs, bolts, nuts and keys.

Still another object of the invention is to provide a side frame having a journal box seat portion provided with means for detachably connecting the side frame and journal box, said attaching means including a member slidably connected to the side frame, extending within the journal box, and co-acting with a removable member therein.

A still further object of this invention is to provide, in combination with a side frame, a key member slidably mounted thereon, said key being adapted to engage a removable member within the journal box for interlockingly connecting the journal box and side frame, and said key being removable only when the cooperating member within the box is disposed from its normal position.

There are other objects of the invention as will more fully hereinafter appear from the detail description of the same when taken in connection with the illustration of the invention on the accompanying drawings, in which:

Figure 1 is a transverse vertical sectional view through a journal box and cooperating side frame showing the invention applied thereto.

Figure 2 is a central longitudinal sectional view of the construction shown in Figure 1.

Figure 3 is a side elevational view of the construction shown in Figure 1.

Figure 4 is a view similar to Figure 2 showing the box and frame separated, the

locking member being omitted from the 55 figure.

Figure 5 is a view in side elevation of a modified side frame and journal box connected by substantially the means shown in the preceding figures. 60

Figure 6 is a view similar to Figure 2, showing, however, the modified construction of Figure 5.

Figure 7 is a view in side elevation of still another modified form of said frame 65 and journal box.

Figure 8 is a view partially in front elevation and partially in vertical section of the construction shown in Figure 7.

Throughout the several views like parts 70 are designated by like reference characters.

Referring to Figures 1 to 4, inclusive, the numeral 1 designates one of the jaw ends of a cast steel side frame adapted for the reception of a separable journal box. 75 The said side frame comprises an upper arch or compression member 2 and a lower arch or tension member 3, the latter being provided with a portion 4 adapted to conform to the upper portion 5 of a journal 80 box 6. The portion 4 is preferably reinforced at its center by a web 7, the latter being connected to the side walls 8 and to the compression member 2 of the side frame. Depending from the portion 4 are the jaw 85 members 9 of the side frame which are adapted to embrace the side walls 10 of the journal box 6, the said side walls being preferably provided with outwardly extending lugs 11 which, when the parts are in normal 90 position, are adapted to engage the outer faces 12-12 of the jaw members 9 to prevent lateral movement of the box 6 with reference to the side frame. The roof 13 of the journal box is provided in alignment with 95 the side frame with an upstanding lug or projection 14 which engages the face 15 of the portion 4. The side edges 16 of the lug or shoulder 14 lie between the downwardly extending flanges 17 and 18 formed on the 100 opposite lateral edges of the face 15.

The jaw members 9 are provided with inwardly projecting shoulders 19, the upper faces of which are in alignment with the lower walls of recesses or openings 20 and 21, respectively, formed in the vertical webs of the jaw members 9. The opening 20 is preferably rectangular in outline while the

opening 21 has its upper wall formed by the lower face of the tension member 3 and hence is wedge-shaped in cross section. The side walls 8 which connect the lateral edges of the tension and compression members preferably extend beyond the opening 20 and are connected at a point above said opening by the horizontally extending flange 22 and by a downwardly extending flange or web 23 in which I provide an opening 24 in alignment with the opening 20 and a further opening 25 adjacent the intersection of the flange 23 with the lower end of the adjacent jaw 9. The opposite jaw 9 is preferably reinforced and strengthened by connecting its lower extremity to the tension member 3 by webs or flanges 26. The journal box 6 has the side walls 10 thereof inset, as at 27, to provide on the interior of the journal box 20 guide lugs for the wedge and journal bearing and on the exterior faces of the box recesses 28-28 for the reception of the lugs or shoulders 19 hereinbefore described.

Within the box I have illustrated the standard A. R. A. construction comprising a wedge member 29 and a bearing member 30, the latter being illustrated as provided with a liner 31 for direct engagement with the bearing portion 32 of the axle 33. The wedge 29 is maintained in position against movement outwardly of the journal box by the lug 34 depending from the roof 13 thereof and from movement in the opposite direction by the lug 35 formed on the bearing member 30. The bearing member, as is usual, is provided with rearwardly facing shoulders, not shown, to engage the outer faces of the guide lugs 27 of the journal box and is, by this means, prevented from 40 moving rearwardly and is held from forward movement by the collar 36 on the axle 33.

The box 6 is provided with a transversely extending opening 37 which, in this form, is 45 located partially in the vertical faces of the guide lugs 27 and partially in the interior of the roof of the journal box, preferably in alignment with the lug 14. In other words, the recess 37 forms a downwardly opening groove within the roof of the journal box, the depth of the opening in the side walls extending below the plane of the roof 13, as clearly shown in Figures 1, 2 and 3. The openings 20, 37 and 21 are 50 adapted to receive a locking bar 38, the latter being provided intermediate its ends with an undercut recess 39 of a width to permit of the entry therein of the wedge block 29, the depth of said opening being such that 55 the wedge block has an extended bearing on the bar 38 as well as on the adjacent portions of the roof 13. The undercut recess 39 is provided with squared shoulders 40-40, said shoulders in the normal position of 60 the parts being adapted to overlie the ad-

jacent portions of the said wedge 29. Said bar 38 has its end 41 substantially conforming to the shape of the recess 39, its opposite end 42 being rectangular so as to conform to the shape of the recess 20 and being further provided adjacent the end 42 with a down-turned lug 43.

From Figures 1 and 2 it will be seen that when the bar 38 is in position the wedge member 29 is seated within the recess 39 and lateral movement of the bar is prevented by the interengagement of the shoulders 40 with the adjacent vertical face of the wedge. Should it be desired to withdraw the bar 38 so as to permit of the detachment of the journal box, it is only necessary to raise the journal box with reference to the axle to such a position that the wedge member 29 may be slid outwardly of the journal box without interference by the lug 34. As soon as the wedge member is withdrawn the bar 38, by means of the lug 43, may be pulled laterally from within the recess within the journal box and from within the openings 21 and 20, at which time the journal box may be slid from between the jaw members 9. To reassemble the parts, it is only necessary to insert the journal box, to then insert the lock bar 38, to then replace the wedge and bearing, and to lower the journal box so that the bearing member engages behind the shoulder or collar 36 of the axle 33 at which time the parts are again locked in position without possible chance of disengagement until the operation above described is repeated.

Referring now to Figures 5 and 6, the construction shown therein is substantially identical with the structure hereinbefore described, the only difference being in the type 103 of jaw members 9^a and in the slightly different construction of the journal box 6^a. The same type of locking bar 38 is employed and the locking bar cooperates with the journal box 6^a and the wedge member 29 110 in exactly the same manner as has hereinbefore been described. The jaw members 9^a are of less extent than the jaw members 9 and the journal box is provided with thickened bearing portions 44 to engage the vertical faces of the jaw members 9^a to assist in maintaining the box against rotation. The side frame 1^a is of the cast steel type and is provided with an angularly disposed web 7^a 115 arranged in alignment with the tension member 3^a rather than the vertical web 7, as previously described.

With this description it is believed that the construction of Figures 5 and 6 will be clearly understood.

In Figures 7 and 8 I have illustrated a modified side frame in which the jaw members 9^b are substantially of the pedestal type and in which the journal box 6^a is substantially identical with the journal box 6 ex- 130

cept for the slight change in the contour of the upper portion of the box. The journal box 6^b is provided with a transversely extending opening 37^b which is preferably substantially identical with the opening 37 of the journal box 6. The co-acting openings 20^b and 21^b in the jaw members 9^b are both, however, not only rectangular in outline but rectangular in cross-section. The lock bar 38^b is provided with correspondingly formed end portions 41^b and 42^b. Except for the changes as herein noted, the construction and operation of this modification are identical with that shown in Figures 1 to 4 and heretofore described in detail.

While I have illustrated and described the locking bar as being located in alignment with the guide lugs of the journal box, it will be understood that this is done merely for convenience and that I consider within the scope of my invention any construction in which a journal box and side frame are interlocked by a transversely extending member carried by the side frame, and in the illustrated embodiments designated as 38 and 38^b, which member cooperates with a removable member within the journal box, and in the present instance designated as 29, to prevent its accidental withdrawal.

It will therefore be understood that the language used in describing the invention, either in the specification or claims, is to be taken in its broad and not in its limiting sense.

Having now described my invention, what I claim is:

1. The combination with a side frame having a journal box engaging portion, of a journal box therefor, a wedge therein, and means for interlockingly connecting said frame and box, said means being adapted to cooperate with said wedge intermediate the ends thereof to prevent undesired withdrawal of said means.

2. The combination with a side frame having a journal box engaging portion, of a journal box cooperating therewith, a wedge within said box, said box having a lug thereon extending into the plane of said wedge, and means for interlockingly connecting said frame and box, said means and said wedge having cooperating portions for holding the means against undesired withdrawal.

3. The combination with a side frame, of a journal box therefor, a wedge within said box, means slidably connected to said side

frame for connecting said box and frame, said means being adapted to extend within said box, and cooperating shoulders on said means and wedge for interlocking said means to said journal box.

4. The combination with a side frame having a journal box engaging portion, of a journal box cooperating therewith, means within said box for cooperating with a car axle, said means being adapted to be interlockingly maintained within said box when said axle is in normal position, and means mounted on said side frame and movable into said box for interlockingly connecting said box and frame, said last named means being adapted to engage said first named means.

5. The combination with a side frame having a journal box engaging portion, of a journal box cooperating therewith, means within said box for cooperating with a car axle, said means being adapted to be interlockingly maintained within said box when said axle is in normal position, and removable means cooperating with said side frame and extending transversely through said box for interlocking said box and frame.

6. The combination with a side frame having a journal box engaging portion, of a journal box cooperating therewith, means within said box for cooperating with a car axle, said means being adapted to be interlockingly maintained within said box when said axle is in normal position, said box and frame having aligned openings therein, and a removable member extending through said openings for interlocking said box and frame, said member being adapted to engage said means to prevent the accidental removal of said member.

7. The combination with a side frame having a jaw portion adapted to engage a journal box, of a journal box fitting within said jaw portion, a wedge and bearing within said box, cooperating means on said box and car axle for maintaining said wedge and bearing against displacement under normal conditions, said box and side frame having aligned openings, and a removable bar extending through said openings for preventing the detachment of said journal box, said bar and wedge having cooperating shoulders to prevent the displacement of said bar when said wedge is in normal position.

In testimony whereof I affix my signature.
DONALD S. BARROWS.
